SPRAYING APPARATUS

Edward O. Norris, Westport, Conn.

Application May 16, 1956, Serial No. 585,239

1 Claim. (Cl. 299—63)

This invention relates to spraying apparatus and more particularly to a centrifugal distributor having inherent directional characteristics.

An object of the invention is to provide a rotary distributor which is adapted to eject a spray of material around its entire periphery, but in which the major portion of the spray is ejected from a limited angular segment of the periphery the radial direction of which can be readily controlled.

Another object is to provide a rotary centrifugal distributor which does not require an external rotary bowl for its directional effect.

Another object is to provide a directional centrifugal distributor which is open to the spray zone around its entire periphery.

Another object is to provide a rotary centrifugal distributor of the above type having novel and improved details of construction and features of operation.

Various other objects and advantages will be apparent as the nature of the invention is more fully disclosed.

The invention will be better understood by referring to the following description, taken in connection with the accompanying drawings in which a specific embodiment thereof has been set forth for purposes of illustration.

In the drawings:

Fig. 1 is a vertical transverse section through a spray chamber showing the arrangement therein of a plurality of centrifugal distributors embodying the present invention;

Fig. 2 is a partial section through a distributor embodying the present invention taken along the lines 2—2 of Fig. 3;

Fig. 3 is an axial section through the distributor and distributor housing;

Fig. 4 is a partial axial section of a distributor illustrating a further embodiment of the invention;

Fig. 5 is a partial radial section of a distributor illustrating a further embodiment; and

Fig. 6 is a diagrammatic view illustrating the spray distribution around the periphery of the distributor.

Referring first to Fig. 3 the distributor shown as comprising a rotary head 10 having a substantially cylindrical peripheral flange 11 terminating in an outwardly flared conical flange 12. Between the flanges 11 and 12 the head 10 is closed by an annular inwardly extending lip 13 in which a closure cap 14 is secured by means of a resilient ring 15.

The head 10 is attached by screws 16 to a radial flange 17 which forms a part of a hollow shaft 18 journaled by ball bearings 19 and 20 in a fixed housing 21, an annular conical shield 22 is attached to the flange 17 by the bolts 16 and surrounds the lower portion of the outer periphery of the fixed housing 21 to shield the same from the spray. The housing 21 is carried on a closure bracket 23 by which it is attached to a wall 24 of the spray chamber to be described. The shaft 18 carries at its upper end (as seen in Fig. 3) a pinion 27 which is driven by a

2

gear 28 which is mounted on an external shaft not shown and is driven by any suitable source of power.

The peripheral flange 11 of the head 10 is provided with a series of peripheral slots 30 which are inclined to the axis of the head 10 as shown in Fig. 3 with their lower ends trailing in the direction of rotation of the distributor, and are also inclined radially as shown in Fig. 2 with their outer edges trailing in the direction of rotation of the distributor, as indicated by the arrow.

10 The material to be sprayed is fed through a fixed but adjustable pipe 32 which extends through the hollow shaft 18 and is provided at its upper end (as seen in Fig. 3) with a flange 33 which is clamped by a nut 38 against a boss 34 on a cap 35 attached by screws 36 to the housing

15 21. The upper portion of the pipe 32 is formed with a flattened portion 39 to receive a wrench for adjusting purposes.

A headed pin 41 having an axial passage 42 is threaded into the lower end of the fixed pipe 32. A shield 43 is threaded onto the end of the fixed pipe 32 and is provided with a peripheral surface 44 having a running fit with the corresponding surface of the flange 17 to prevent spray liquid from working its way along the hollow shaft 18 to the bearings 20 and 19.

25 25 A radial feed pipe 45 is attached to a head 46 which is disposed around the headed pin 41 and is clamped against the shoulder 40 on the shield 43. The radial pipe 45 communicates with the passage 42 in the headed pin 41 by a passage 48 in the head 46. The headed pin 41 permits the head 46 and the feed pipe 45 to be adjusted in any desired angular position about the axis of the fixed pipe 32.

At its outer end the pipe 45 carries an axially extending nozzle 50 having an axial slot 51 disposed adjacent the inner periphery of the flange 11 of the centrifugal spray head 10 and extending axially along substantially the entire axial length of the slots 30 in the flange 11 to cause the material to be ejected as a jet toward and into the moving slots 30.

40 40 In the operation of the device the material for spraying, such as paint, is fed through pipe 32 under pressure and is forced through the radial pipe 45 and outwardly through the slot in the nozzle 50 onto the inner periphery of the flange 11. The rotary head 10 is driven at a high speed by the gear 28 so that the material which is forced onto the inner periphery of the flange 11 flows over the inner surface and is thrown outwardly by centrifugal force through the slots 30. The axial and radial inclination of the slots 30 cause the material to be discharged uniformly thereacross in the form of a spray which extends around the entire 360° of the periphery of the rotating hood. The radial inclination also tends to reduce the noise.

50 55 As shown in the distribution chart of Fig. 6 at least 50% of the total quantity of the material is discharged from the rotating head 10 in the first 90° following the position of the pipe 50. The remainder of the material is discharged from the other 270° of the periphery. Hence the material is directed substantially in the direction shown by the arrow 55 in Fig. 6 and the direction can be altered as desired by varying the position of the feed pipe 45 and the discharge slot 51 around the axis of the distributor.

60 65 When the distributor is rotated at high speed the conical flange 12 serves to create an air current having an axial component in the downward direction which causes the spray from the distributor to fan out in an axial direction, thereby increasing the spray area. Also any spray particles or mist which may be present in the air around the distributor on which may be collected on the inner peripheral surface of the flange 12 are thrown outwardly

therefrom, thereby effectively freeing the air from such particles.

In the embodiment shown in Fig. 4 the distributor head 10a is of the general form of distributor head 10 described above. In Fig. 4 however the flange 11a slopes inwardly in a downward direction to a horizontal lip 13a in which the cover 14a is seated. The slots 30a in the flange 11a of Fig. 4 slope axially and radially as described above in connection with the slots 30 in Fig. 3. The slots 30a of Fig. 4 however have a radial as well as an axial component due to the slope of the flange 11a which assists in distributing the spray material axially of the distributor and in producing a fan-shaped spray.

The embodiment of Fig. 5 is similar to Fig. 4 except that a conical flange 12a is provided below the flange 11a and the feed tube 45a of Fig. 5 extends in a downwardly inclined direction with the nozzle 50a extending upwardly therefrom toward the larger diameter portion of the flange 11a. This arrangement of the feed pipe causes the spray material to flow by centrifugal force toward the larger diameter portion of the flange 11a and to be evenly distributed through the slots 30a as above described.

Fig. 1 shows a spray chamber for spraying a pipe 60 as it is advanced through the chamber supported on double coned rollers 68. The spray chamber of Fig. 1 comprises end walls 24 through which pipe 60 passes and outer walls 61 having hinged top walls 62 which slope at an angle greater than 45 degrees so that any spray material which collects on the inner surface of the wall 62 flows downwardly along the inner surface away from the path of the pipe 60 without dripping onto the pipe. The oversprayed material is collected in a sump 63 at the bottom of the chamber, from which it is removed by a drain pipe 64. The pipe 60 feeds into the chamber through a vestibule 65 having top walls 66 which slope at an angle similar to the walls 62 above described. The chamber may be of the general type shown in my Patent No. 2,734,479, dated February 14, 1956. Four spray heads 10 are shown as disposed on the transverse wall at the exit end of the spray chamber with their flanges 12 facing counter to the direction of

travel of the pipe 60 for the purpose of deflecting the spray in a direction counter to the direction of travel of the objects being sprayed so as to minimize the carry out of the spray. A flexible closure is preferably installed around the entrance opening to minimize direct escape of spray particles. The nozzles 50 in each of the spray heads 10 are so adjusted that the major portion of the spray produced therefrom is directed against the periphery of the pipe 60, thereby reducing the amount of oversprayed material which strikes the walls of the chamber.

It is to be understood of course that the oversprayed material collected and withdrawn through the drain pipe 64 may be recycled and resprayed. The pipe 60 is of course advanced continuously through the spray chamber or articles to be sprayed may be fed through the spray chamber on a conveyor as shown in my previous patent above mentioned.

What is claimed is:

A spray device comprising a fixed casing, a hollow shaft mounted for rotation therein, a head carried by said shaft having a peripheral wall provided with openings spaced therearound through which material is sprayed, a fixed feed pipe for said spray material disposed within said hollow shaft, a nozzle communicating with the end 20 of said feed pipe within said rotating head, said nozzle having a discharge opening disposed adjacent the inner peripheral surface of said head in registration with said first openings to discharge the spray material from said nozzle directly into said first openings for spraying whereby the major portion of the spray material is sprayed outwardly in a limited peripheral segment around said head.
